HARRY SISKIN, OF LOS ANGELES, CALIFORNIA

EXTENSION TABLE

Application filed November 21, 1927. Serial No. 234,707.

This invention relates in general to an extension table and has more particular reference to a sectional sliding table top with foldable extension leaves concealed below the top.

5 In an extension table it is some times desirable to insert only a single extension leaf, but two or more extension leaves of this kind may also be inserted if desired. Where there are two extension leaves and the table top 10 consists of two oppositely moving sections, it is necessary to provide means for centering each of the folding leaves between the extension top sections. When the extension leaf is removed it is necessary to position it at one 15 side of the other leaf in order that it may fold below the table top, and to insure that it will be free from contact with the other table leaf.

An important object of the invention is in the provision of means in connection with the 20 table top sections for positioning either or both of a pair of folding leaf sections so that they may be properly stored below the table top when the leaves are rotated to their concealed position. A further object of the invention is in the provision of non-interfering 25 selective means for engaging and withdrawing either one or both of a pair of folding table leaves from a central position to a lateral position in which they may be inverted below 30 the table top. Other objects will appear hereinafter, the drawings illustrating a preferred embodiment of the invention. In the drawings;

35 Figure 1 is a plan view with parts broken away for clearness of an opening extension table constructed in accordance with the principles of this invention;

Figure 2 is a sectional view taken on the line 2—2 of Figure 1; and

40 Figure 3 is a sectional view showing one of the extension leaves in its open or extended position.

This invention is shown as applied to a stationary table base 4 which has a pair of top 45 sections 5 and 6 movable oppositely at the top of the table base by means of opposite metal racks 7 and 8 secured to the under side of each table section and engaging at the center with a pinion 9 which causes the opposite 50 relative movement of the top sections.

In order to hold the table top sections together, a pivoted latch 10 is mounted at the under side of one of the table sections and has a fixed catch 11 engaged thereby at the under side of the opposite section. To release the 55 catch 10 an operating rod 12 having an engaging head 13 is carried by one of the top sections and is movable to release the latch 10 when it is desired to extend the table top.

As the table top sections 5 and 6 are connected for simultaneous opposite movement, a single extension leaf must be centered between them when it is desired to increase the size of the table top by one leaf only.

5 In the present invention provision is made for a pair of folding leaves which are concealed below the table top in closed position and either one or both of these folding leaves may be inserted and centered between the table top sections, and either one or both of 70 the extension leaves will be withdrawn to the proper position when the table top sections are moved apart in reducing the size of the table.

To accomplish this result, a pivoting rod 15 75 extends lengthwise of the direction of movement of the table top sections 5 and 6 and is fixed at the ends of the supporting base 4 or frame of the table. Pivoted upon the rod 15 are a pair of folding sectional table leaves, 80 each comprising sections 16 and 17 connected by a hinge 18 invisible from one side of the leaf thus formed when the leaf is unfolded or extended. The uppermost section 16 in folded position is provided with brackets 19 85 and 20 each having a perforated upstanding leaf through which the rod 15 extends, one located close to the outer edge of the table leaf and the other bracket 20 spaced at a distance less than one half of the width of the 90 table leaf from the opposite or inner edge thereof. In its folded and concealed position below the table top, the folding leaves may be supported in any suitable manner, as, for example, by means of a rod 21 which extends 95 parallel with the pivoting rod 15 and at one side thereof.

Hooks 22 and 23 are secured to the under sides of the table top sections 5 and 6, extending inwardly toward each other and in position 100

tion to engage the upstanding leaf of the outermost bracket 19 of the folding leaf adjacent thereto but not engaging the upstanding leaf of the bracket 20 which is reduced in width adjacent the pivoting rod 15 so that the hook 22 or 23 will pass by the upstanding reduced leaf portion of bracket 20 in either direction but will engage the upstanding leaf of bracket 19 which is of full width. One of the hooks 22 or 23 is offset with respect to the other so that when the table top sections are moved together these hooks will not engage but will pass freely by each other, allowing the top sections to move close together where they may engage and are held in this position by the latch 10.

With this construction it is obvious that either leaf may be rotated by the pivoting rod 15 when the table top sections are moved apart, and when the sections are moved together the unfolded leaf will be confined at the center of the table between the two top sections. In withdrawing the extension leaf this action is reversed. The table top sections are first moved apart; with this construction the proper hook 22 or 23 will engage its corresponding bracket 19 as the top sections are moved apart and will withdraw the centered folding leaf to its proper position without separately and manually engaging and operating the leaf. The extension leaf is then folded or collapsed and rotated below the level of the table top into its concealed position.

35 The inner brackets 20 are located, as explained, so that either leaf may partially overlap the other without causing an engagement of the brackets 20 and each bracket 20 is cut away so that the hooks 22 and 23 will pass by them without engagement.

If both extension leaves are unfolded and extended, it is apparent that they will both be returned by their respective hooks 22 and 23 as the table top sections are moved apart.

45 It will be observed that provision is made for spacing the folding leaves apart and from the adjacent edges of their respective table top sections a distance sufficient to clear the dowel pins which are commonly employed with extension tables and leaves to hold the parts in proper alignment when they are moved together.

While I have thus disclosed a preferred embodiment of my invention, it is obvious 55 that various changes may be made without departing from the spirit and scope of my invention.

I claim:

1. An extension table comprising movable top sections and means for moving them oppositely in unison, an extension leaf mounted eccentrically below the top in concealed position and movable laterally for centering it between the top sections in extended position, and means in connection with one of the table

top sections for moving the extension leaf to its eccentric position when the top sections are moved apart.

2. In an extension table, a pair of top sections connected for joint opposite movement, a foldable leaf mounted to swing below the table top at one side of the center into concealed position, means for laterally sliding and centering the table leaf between the top sections in extended position, and means in connection with the table top sections for automatically withdrawing the leaf from a central position to its proper position at one side of the center when the table top sections are moved apart in collapsing the table.

3. A folding leaf structure, comprising table top sections movable toward and from a central abutting position, a pair of folding table leaves mounted to swing side by side below the top and to be centered alone and in conjunction between the top sections, and means in connection with each top section for withdrawing the corresponding leaf from a centered position to its proper position at one side of the center when the top sections are moved apart in collapsing or reducing the size of the table.

4. In an extension table, a pair of oppositely moving top sections, a folding leaf movable from a position below the level of the top to a position in alignment with the top sections, and means comprising a bracket in connection with the folding leaf, and a hook in connection with one of the table top sections for moving the folding leaf in one direction but not in the other with one of the table top sections.

5. In an extension table, a pair of oppositely movable top sections, folding table leaves disposed below the top at opposite sides of the center thereof, means comprising brackets for mounting the leaves to swing from a concealed to an unfolded position, and hooks projecting from the inner edges of the top sections and adapted to engage the adjacent brackets for moving the folding leaves to their proper positions at the sides of the table center when the top sections are moved apart in reducing the size of the table.

6. In an extension table, a pair of oppositely movable table top sections, a pivoting rod extending parallel with the direction of movement thereof, a pair of folding leaves movable from below the table top to a position in alignment therewith, brackets for mounting the leaves to swing upon said rod, a hook projecting inwardly from each top section to engage the bracket of the adjacent table leaf for moving the corresponding leaves apart and from a central position between the top sections when the top sections are moved apart in reducing the size of the table.

7. In an extension table, a pair of oppositely moving top sections, a pair of foldable

- leaves, brackets for mounting the leaves to rotate from a concealed position below the top to an unfolded position in alignment with the top section, an inner bracket of each
- 5 leaf being disposed at a distance from the edge to permit one leaf to overlap the other a distance approximately one half of the width of the other leaf in centering an unfolded leaf between the table top sections
- 10 above a folded leaf in extending the table, and means in connection with the top sections for withdrawing the unfolded leaf to its position at one side of the center when the top sections are withdrawn in reducing
- 15 the size of the table.
8. In an extension table, a pair of opposite table top sections, folding leaves pivotally mounted in the table below the top thereof and unfoldable in alignment with the top,
- 20 means for mounting the leaves for rotating movement in the table comprising a pair of brackets, one having a pivoting leaf wider than the other, and a hook carried by each of the top sections and adapted to engage the
- 25 wider leaf of each adjacent bracket but movable past the reduced leaf of the other brackets whereby each folding leaf is drawn laterally with its corresponding table top section in reducing the size of the table.
- 30 9. In an extension table, a pair of table top sections connected for joint opposite movement, releasable means for holding the table top sections together when the table is in its reduced size, a pair of folding extension leaves disposed lateral of the table center in their folded position, means for mounting the leaves for rotation in alignment with the top sections comprising a bracket adjacent the outer edge of each leaf and another
- 35 bracket spaced a distance from the inner edge of each leaf, the inner bracket of each leaf having a pivoting portion of less width than the outer bracket, a pair of hooks one extending inwardly from the edge of each top section and adapted to engage the outer bracket of its corresponding leaf but moved past the inner bracket of the corresponding leaf, the opposite hooks being at different elevations so that they will pass each other when the top
- 40 sections are moved together, the hooks engaging the wider brackets to draw the leaves apart and to space the leaves from the top sections so that the aligning dowel pins will be cleared when the table top sections are
- 45 moved apart in reducing the size of the table.
- 50
- 55

HARRY SISKIN.
